UNITED STATES PATENT OFFICE.

EDWARD M. COOK, OF OBERLIN, OHIO.

SHOE-HEEL.

1,290,095.

Specification of Letters Patent.

Patented Jan. 7, 1919.

Application filed June 7, 1918. Serial No. 238,760.

To all whom it may concern:

Be it known that I, EDWARD M. COOK, a citizen of the United States, residing at Oberlin, in the county of Lorain and State of Ohio, have invented new and useful Improvements in Shoe-Heels, of which the following is a specification.

This invention relates to shoe heels and more particularly to cushion heels formed of rubber or other elastic material and designed for application to shoes.

The primary object of the invention is to provide a heel of the above character with a gripping means upon its tread surface, the said means being formed by providing the heel with a concaved upper surface for contact with the shoe, with a bead or rib along the front edge of the shoe either at the top or bottom edge, the manner of securing the heel upon the shoe causing the concaved surface to be transferred to the lower face of the heel to provide the tread with suction gripping means.

In the drawings:

Figure 1 is a sectional view of a fragmentary portion through the heel end of the shoe with the improved heel applied thereto;

Fig. 2 is a detail sectional view of the heel;

Fig. 3 is a bottom plan view of the same. Referring to the drawings in detail, there is shown a heel designated at 10 and formed of rubber or other elastic material. This heel is provided with a concaved upper surface 11, which is designed for contact with the shoe when secured in position thereto, the fastening devices 12 drawing the concaved surface flat against the surface of the shoe with which it contacts. The lower or

tread surface 13 of the heel is substantially flat and is provided along its front edge with a transverse rib 14, having side wings 15 which taper off flush with the tread surface.

When the heel is secured in position upon a shoe and the upper surface 11 is drawn into close contact with the shoe, the body of the heel will be flexed and the concavity transferred to the tread surface 13, the rib 14 and the side walls 15 together with the surrounding edge of the heel providing a suction gripping means which will take hold of the surface being walked upon and prevent the wearer from slipping.

Having described the invention, what is claimed is:

1. A shoe heel formed of compressible material embodying a concaved upper surface, a flat tread surface, a rib extending across the lower edge of the last mentioned surface and tapering side wings provided at each end of the rib, the concaved upper surface being adapted to be secured in close contact to the heel of the shoe in a manner to provide a concaved tread surface for engagement with the ground.

2. A shoe heel formed of compressible material and embodying a concaved upper surface, a flat tread surface, a rib extending across the lower front edge of the last mentioned surface and side wings extending rearwardly from each end of said rib, said wings tapering and merging into the lower surface of the heel, which, together with the rib define a depression and form an inclined surface upon the bottom of the heel.

In testimony whereof I affix my signature.

EDWARD M. COOK.
